UNITED STATES PATENT OFFICE.

JOHN A. LAFORE, OF CYNWYD, PENNSYLVANIA.

VACUUM-PUMP OR COMPRESSOR.

1,009,908.

Specification of Letters Patent. Patented Nov. 28, 1911.

Application filed March 14, 1911. Serial No. 614,381.

To all whom it may concern:

Be it known that I, JOHN A. LAFORE, a citizen of the United States, residing in Cynwyd, in the county of Montgomery and State of Pennsylvania, have invented a certain new and useful Vacuum-Pump or Compressor, of which the following is a specification.

My invention relates to apparatus in the nature of a vacuum pump for withdrawing air, gas, or similar "fluid" from its container, or a compressor for raising such a fluid from lower pressure to higher pressure.

In the practice of my invention, I employ a liquid, such as water, for producing the action above described, the liquid being employed as separated portions for moving the fluid to raise the same from a lower to a higher pressure, as, for example, by exhausting the air or other fluid from a condenser or other chamber.

In my apparatus I provide an inlet for the liquid, an outlet for the liquid and fluid, and an inlet for the fluid between the inlet for liquid and the outlet for liquid and fluid; or I provide an inlet for both liquid and fluid and an outlet for both liquid and fluid.

My invention resides in the apparatus hereinafter described and claimed.

For an illustration of only some of the forms my invention may take, reference is to be had to the accompanying drawing, in which:

Figure 1 is a cross sectional view through a form of my invention involving a rotary part for carrying out the principle illustrated in Fig. 1. Fig. 2 is a cross sectional view at right angles to the view shown in Fig. 1. Fig. 3 is a cross sectional view of a modification of the form of apparatus shown in Fig. 1. Fig. 4 is a simplified or diagrammatic view illustrating my invention, associated with a condenser for steam or the like. Fig. 5 is a simplified or diagrammatic view illustrating my invention in combination with a barometric condenser. Fig. 6 is a fragmentary view illustrating a form of my invention in which the rotary part of the apparatus is not driven by a separate motor or prime mover, but by the liquid or water itself.

In Figs. 1 and 2, there is shown within a casing 15 a rotary impeller wheel 16 with a plurality of passages 17 communicating with the liquid or water inlet 18. The impeller 16 is secured upon a driving shaft 19

extending outside of the casing 15 and having thereon a pulley 20 for rotating the impeller as driven by a motor, engine or other suitable device. Outside of the impeller 16 is the stationary continuous ring 21 having a plurality of vanes 22 and substantially uniformly distributed around its circumference. Between the vanes 22 are formed the passages 23 all communicating at their outer ends with the discharge passage 24, here shown in the form of a volute having the exit at 25. The passages 23 are tubular in that they are more or less elongated and surrounded on all sides, except at their end openings, by an inclosing wall. While these passages are stated to be tubular, it is not to be understood that the cross section of the passages is necessarily circular, but may be of any suitable shape, and as here illustrated, are not circular in cross section. Between the vanes 22 and communicating with the passages 23 is the series of ports or openings 26 which all communicate with the annular chamber 27, which latter communicates through the opening 28 with the open atmosphere, in the case that air is to be compressed, or which communicates with a chamber containing the air or other fluid which is to be exhausted from such chamber.

The number of passages 17 in the impeller 16 may be made anything desired, and the direction of curving of the passages, or the direction of extent of the passages, may be made anything suitable or desirable; but there should be substantial separation between the peripheral outlets of passages 17, whereby intermittent flow of liquid through each passage 23 is insured.

As viewed in Fig. 2, the direction of rotation of the impeller 16 is clockwise, as indicated by the arrow.

In operation, the liquid or water is admitted at 18 and passes to the inlet of the impeller 16, and while the impeller is being rotated at suitable speed, discharges at the periphery of the impeller and passes out through the passages 23 between the vanes 22 into the discharge passage 24. The effect is, considering any one impeller passage 17, to discharge through successive passages 23 masses of water. These pass the fluid or air openings 26, which in Fig. 2 are shown as preferably inclined outwardly, and small masses of air are entrapped or sucked from the passage or chamber 27 and carried with

the water into the discharge passage 24 being ultimately discharged together at 25 from the apparatus. It will be noted, therefore, that the fluid or air inlet, as at openings 26, is at a point between the liquid or water inlet and the discharge passage or outlet for combined water and air or liquid and fluid. The passages 23 may be constricted as at 29, if desired.

16 The shapes of the vanes 22 and of the passages 23 may be made anything suitable or desirable, it being understood that my invention is not limited in this respect to the shape disclosed in the drawing. It is to be understood that the inclination of the vanes 22 and passages 23 may be made anything suitable or desirable, and that my invention is not limited to the inclination illustrated in the drawing.

20 In Fig. 3 the parts are similar to those shown in Figs. 1 and 2, except that the passages 26 for the air or fluid are not located so definitely in passages 23, but communicate with the passages 23 at their inner edges 25 where the impeller passages 17 communicate with said passages 23. That is to say, instead of the passages 26 being made through the material surrounding the passages 23 of Figs. 1 and 2, they are made 30 through the material just at or just within the inner bounding circle of the vanes 22 and passages 23 of Fig. 2. By this construction, there is provided an inlet for both liquid and fluid and an outlet for both liquid 35 and fluid. In Fig. 3, since the location is different in these respects, the passages 26 need not be separate openings but may be a circumferentially continuous narrow slit or opening.

40 As is obvious to any one skilled in hydraulics, the pulleys 20 may be omitted and the impellers or runners 16 of Figs. 1, 2 and 3 may be driven by the water itself which is admitted to them under pressure, the direction of the passages 17 in the impeller or runner being made suitable for rotating the impeller or runner under the water pressure itself and the inclination of the vanes 22 and passages 23 being correspondingly suited. This arrangement is shown simply in Fig. 6, where no driving pulley is provided.

45 In Fig. 4 my rotary apparatus is shown as having its fluid or air inlet 28 connected to the barometric or other condenser 30 whose outlet for water and condensed steam is indicated at 31, the condensing water inlet at 32 and the steam inlet at 33.

50 In Fig. 5 my rotary apparatus is shown in combination with the barometric condenser 34 having the barometric column 31 with condensing inlet 35 and steam inlet 36. The fluid or air inlet 28 of my apparatus is shown connected to the condenser 34. My apparatus here, however, is not supplied with a pulley for driving the impeller, but

the impeller is driven due to the fall of water through the barometric column 37. It is to be understood that this figure is diagrammatic only but that in practice the barometric column 31 of the condenser 34 70 would be larger in diameter than the column 37 connecting with the fluid and liquid discharge 25 of my apparatus, and that this figure is not intended to indicate proportions but merely the matter of arrangement. 75

From the foregoing description it will appear that I have provided apparatus having a rotary part, which will exhaust fluid or air or compress the same by admitting the fluid or air at a point between the inlet 80 for the liquid, and the discharge for the liquid and fluid; or by admitting the fluid or air at substantially the same point with the liquid.

It will be noted also that my impeller 16 85 is a total influx or efflux impeller, that is to say, the water flows through all its passages continuously.

It is to be understood that I do not wish to be limited to the proportions illustrated in 90 my drawings which are simply illustrative of the principles of my invention. For example, in Figs. 1 and 3, the air passages 28 may in actual practice be larger than the water passages 18 or may have any suitable 95 relative proportions.

For the sake of simplicity I employ in the appended claims the term "air" as applying to air, gas, or similar fluid hereinbefore referred to, and I employ the term "water" 100 as applying to water or any other liquid.

What I claim is:

1. In apparatus of the character described, the combination with a member having a tubular passage having an inlet for water and an outlet for air and water, of a movable member having a water passage for intermittently delivering water into said first mentioned passage, and means for admitting air to said first mentioned passage 105 at a point between said inlet for water and said outlet for water and air. 110

2. In apparatus of the character described, the combination with a member having a tubular passage having an inlet for water and an outlet for air and water, of means for admitting air to said passage between said inlet and outlet, and means for intermittently delivering water into said inlet. 115

3. In apparatus of the character described, the combination with a member having a tubular passage having an inlet for water and an outlet for air and water, of means for admitting air to said passage between said inlet and outlet, and means for intermittently delivering water at high velocity into said inlet. 120

4. In apparatus of the character described, a member having a plurality of tubular passages each having an inlet for water and an 130

5 outlet for air and water, means for admitting air to each passage at a point between its inlet and its outlet, and means for delivering water into the inlets of said passages in succession.

6. In apparatus of the character described, a member having a plurality of tubular passages each having an inlet for water and an outlet for air and water, means for admitting air to each passage at a point between its inlet and its outlet, and a rotary member delivering water at high velocity into said inlets in succession.

7. In apparatus of the character described, the combination with a rotary impeller having a water passage therein, of a stationary member surrounding said impeller and having a plurality of independent tubular passages through which water is delivered in succession from said impeller passage, means for admitting air to said passages in said stationary member independently of said impeller, a discharge casing surrounding said stationary member and receiving the air and water discharged from said passages in said stationary member, and an outlet from said discharge casing for carrying off the air and water.

8. In apparatus of the character described, the combination with a rotary impeller having a water passage therein, of a stationary member surrounding said impeller and having a plurality of independent tubular passages through which water is delivered in succession from said impeller passage, and means for admitting air to said passages at points between their inlets and outlets.

9. In apparatus of the character described, the combination with a rotary impeller having a water passage therein, of a stationary member surrounding said impeller and having a plurality of independent tubular passages through which water is delivered in succession from said impeller passage, means for admitting air to said passages at points between their inlets and outlets, and a discharge chamber surrounding said stationary member and receiving the water and air discharged from said passages in said stationary member.

10. In apparatus of the character described, the combination with a rotatable impeller having a water passage sloping outwardly and backwardly with regard to the direction of rotation, of a stationary member surrounding said impeller and having a plurality of independent tubular passages receiving water from said impeller in succession, said passages in said stationary member extending outwardly and forwardly with regard to the direction of rotation of said impeller, a discharge casing surrounding said stationary member common to said passages in said stationary member, and means for delivering air to said passages in said stationary member independently of said impeller at points between the periphery of said impeller and the outlets of said passages into said discharge casing.

11. In apparatus of the character described, the combination with a rotatable impeller having a water passage sloping outwardly and backwardly with regard to the direction of rotation, of a stationary member surrounding said impeller and having a plurality of independent tubular passages receiving water from said impeller in succession, said passages in said stationary member extending outwardly and forwardly with regard to the direction of rotation of said impeller, a discharge casing surrounding said stationary member common to said passages in said stationary member, and means for delivering air to said passages in said stationary member independently of said impeller at points between the periphery of said impeller and the outlets of said passages into said discharge casing.

12. In apparatus of the character described, the combination with a rotatable impeller having a water passage sloping outwardly and backwardly with regard to the direction of rotation, of a stationary member surrounding said impeller and having a plurality of independent tubular passages receiving water from said impeller in succession, said passages in said stationary member extending outwardly and forwardly with regard to the direction of rotation of said impeller, a discharge casing surrounding said stationary member common to said passages in said stationary member, and means for delivering air to said passages in said stationary member independently of said impeller at points between the periphery of said impeller and the outlets of said passages into said discharge casing.

13. In apparatus of the character described, the combination with a rotatable impeller having a water passage sloping outwardly and backwardly with regard to the direction of rotation, of a stationary member surrounding said impeller and having a plurality of independent tubular passages receiving water from said impeller in succession, said passages in said stationary member extending outwardly and forwardly with regard to the direction of rotation of said impeller, a discharge casing surrounding said stationary member common to said passages in said stationary member, and means for delivering air to said passages at points between the inlets and outlets of said passages.

14. In apparatus of the character described, a rotatable impeller having a water passage therein, of a stationary member surrounding said impeller and having a plurality of separate tubular passages, a casing inclosing said impeller and said stationary member, and an annular air chamber having means for admitting air to said separate passages in said stationary member.

15. In apparatus of the character described, a rotatable impeller having a water passage therein, of a stationary member surrounding said impeller and having a plurality of separate tubular passages, a casing inclosing said impeller and said stationary member, and an annular air chamber having a plurality of passages communicating with said separate passages in said stationary member at points between their inlets and outlets.

16. The combination with a condenser, of a rotatable impeller having a water passage therein, a stationary member surrounding said impeller and having a plurality of independent tubular passages, means communicating with said separate passages in said stationary member at points between their inlets and outlets, and a discharge casing surrounding said stationary member and receiving water and air from said passages in said stationary member.

1
nating with said condenser and delivering air therefrom to said independent passages in said stationary member, a discharge casing surrounding said stationary member and 5 receiving air and water from said passages, and an outlet for said discharge chamber for delivering air and water.

15. In apparatus of the character described, a rotatable impeller having a water 10 passage therein, a stationary member surrounding said impeller and having a plurality of independent tubular passages, a casing inclosing said impeller and said sta-

tionary member, a discharge passage in said casing, an annular air chamber having 15 means for admitting air to said separate passages in said stationary member, a condenser, and means for delivering air from said condenser to said annular chamber.

In testimony whereof I have hereunto affixed my signature in the presence of the two subscribing witnesses.

JOHN A. LAFORE.
